Samuel H. Berch, Beverly Hills, Calif., assignor,
by mesne assignments, to Diced Cream of
America Co., Los Angeles, Calif., a corporation
of Delaware

Application July 19, 1947, Serial No. 140,383

Term of patent 14 years

(Cl. D36—8)

To all whom it may concern:

Be it known that I, Samuel H. Berch, a citizen of the United States, residing at Beverly Hills, county of Los Angeles, State of California, have invented a new, original, and ornamental Design for a Goblet, of which the following is a specification, reference being had to the accompanying drawing, forming a part thereof.

Figure 1 is a plan view of a goblet, showing my new design.

Fig. 2 is a view in side elevation thereof, and Fig. 3 is a sectional view taken on line 3—3 of Fig. 2.

I claim:

The ornamental design for a goblet, as shown.
SAMUEL H. BERCH.
